213,454

CLOCK CASING

David W. Miley, Peru, Ill., assignor to General Time Corporation, Stamford, Conn., a corporation of Delaware

Filed Feb. 26, 1968, Ser. No. 10,717

Term of patent 14 years

U.S. Cl. D42—7
Int. Cl. D10—01

FIG. 1

FIG.3

FIG.2

FIG.5

FIG.4

FIG. 1 is a perspective view of a clock casing showing my new design;

FIG. 2 is a front elevational view;

FIG. 3 is a top plan view;

FIG. 4 is a rear elevational view; and

FIG. 5 is a left side elevational view, the side opposite (not shown) has substantially the same peripheral contour, is plain and unornamented.

The broken line showings of a clock face and hands are for illustrative purposes only.

I claim:

The ornamental design for a clock casing, substantially as shown and described.
